UNITED STATES PATENT OFFICE.

RALPH V. SAGE, OF WESTMONT BOROUGH, PENNSYLVANIA.

CAR-STAKE.

No. 827,266.

Specification of Letters Patent.

Patented July 31, 1906.

Application filed June 9, 1905. Serial No. 264,395.

To all whom it may concern:

Be it known that I, RALPH V. SAGE, a citizen of the United States, residing in the borough of Westmont, in the county of Cambria and State of Pennsylvania, have invented certain new and useful Improvements in Car-Stakes; and I do hereby declare the following to be a full, clear, and exact description of the invention, such as will enable others skilled in the art to which it appertains to make and use the same.

My invention relates to railway-cars, and more particularly to stakes or posts for strengthening the sides thereof; and it relates also to flanged metal bars for forming such stakes.

It has for its object to provide a trough-shaped metal car-stake with inclined sides, having an integral enlargement along their adjoining portions and flanges along their free edges to furnish means for securing the stake in position, whereby an economical distribution of the metal is effected.

As herein shown the embodiment of my invention is substantially V-shaped in cross-section, is rounded and thickened at the apex, and is provided with outwardly-extending flanges at the opposite edges, forming a base. Car-stakes of a similar cross-section, but of a uniform thickness of stock, have heretofore been made and have usually been formed by pressing a flat plate into the desired shape. Such a stake made from a plate of uniform thickness has not an economical distribution of the metal for the apex portion, which has a maximum stress, will not have a proportionate strength when the base portion is properly proportioned, and, conversely, when the apex portion is made sufficiently strong the base portion is unnecessarily heavy, making the stake as a whole uselessly expensive. Furthermore, a stake of this type is expensive in consequence of the original cost of the machinery and dies required for its manufacture and the cost of maintaining the same. In my improved stake, however, the apex portion is provided with an integral enlargement, thus compensating for the metal in the base portion and proportioning the parts relative to their stresses, whereby the neutral axis of the section parallel to the base is brought substantially into coincidence with the geometric axis thereof. A stake is thus produced having an economical distribution of metal, thereby reducing the weight and cost proportionate to its strength, and one

which can be cheaply made from a stock bar rolled in long lengths by the ordinary process of rolling metal.

Referring now to the drawings forming a part hereof, in which like characters of reference designate like parts, Figure 1 is a transverse sectional view of my improved stake and a portion of a car side plate to which it is secured, taken on a plane indicated by line I of Fig. 2, showing the enlargement at the apex portion. Fig. 2 is a fragmentary side elevation of a gondola car, showing my stake in position. Fig. 3 is a transverse sectional elevation taken on a plane indicated by the line III III of Fig. 2 viewed in the direction of the arrows, showing the relative position of my stake and the manner of securing it in place.

In the drawings, 1 designates one of the transoms or cross-sills forming a part of the underframe upon which the floor-plate 2 is laid and secured in position. Secured to each of the transoms is the connection angle or bracket 3, and to the floor-plates and transoms is secured the angle 4, which brackets and angle are attached to the web 5 of the side plate-girder. The flange-angles 6 and 7 of the plate-girder are secured, respectively, to the top and bottom of the web-plate, and between their outwardly-extending flanges are located a plurality of my improved sidestakes, as 8. The stakes are secured to the plate-girder web and incidentally to the flange-angles 6 and 7, the angle 4 and the connection-angle 3 in the usual manner serving to strengthen the whole structure.

The stake is preferably made substantially V-shaped in cross-section, as herein shown, in order that there may be no projecting edges or corners for obstructions to catch upon and that it may better resist any lateral pressure that may be placed upon it. The sides 9 of the stake are connected by a rounded apex portion 10, and they are provided with flanges 11 along their free edges, forming a base portion by which the stake is secured in position. In order that the apex portion, which in service is subjected to the maximum stress due to pressure on the car sides, may be properly proportioned relative to the base portion, it is provided with an integral enlargement or thickening, whereby an economical distribution of the metal is effected. The base portion, therefore, need not be made unnecessarily heavy that the apex portion may be sufficiently strong, as would result if the stake

were formed from metal of a uniform thickness, my construction thereby effecting a material saving in the cost thereof. My stake is easily made from a stock-bar which may be 5 rolled in long lengths by the ordinary process of rolling metal and the cost of its production thereby cheapened.

It will readily be seen that my invention is not necessarily limited to a stake which is 10 substantially V-shaped in cross-section, for a variety of other trough-shaped sections have practically an equal efficiency. If found desirable, the stake may also be formed of a plurality of convolutions instead of a single one 15 without departing from the spirit of my invention. It is not the desire, therefore, to limit this application to the specific embodiment of the invention shown and described herein, but to have it construed as broadly as is commensurate with the generic character of the 20 invention.

Having thus described my invention, what I claim as new, and desire to secure by Letters Patent, is—

25 1. A trough-shaped metal car-stake having a side provided with a flange along its free

edge and a thickened integral portion along the edge opposite thereto.

2. A trough-shaped metal car-stake having flanged sides and an integral thickening 30 along the junction of said sides.

3. A trough-shaped metal car-stake having flanged sides which are united by an integral thickening of the metal.

4. A metal car - stake, substantially V- 35 shaped in cross-section having flanged sides and an integral enlargement at the apex.

5. A metal car - stake, substantially V- shaped in cross-section, having flanged sides and a rounded apex portion provided with an 40 integral enlargement.

6. A metal car - stake, substantially V- shaped in cross-section, having sides flanged outwardly at their free edges, and a rounded apex portion provided with an integral thick- 45 ening.

In testimony whereof I hereto affix my signature in the presence of two witnesses.

RALPH V. SAGE.
